US00D660669S

(12) **United States Design Patent**
Teraoka

(10) **Patent No.:** US D660,669 S
(45) **Date of Patent:** ** May 29, 2012

(54) **SOLDERING IRON**

- (75) Inventor: **Yoshitomo Teraoka**, Osaka (JP)
(73) Assignee: **Hakko Corporation**, Osaka (JP)
(**) Term: **14 Years**
(21) Appl. No.: **29/401,567**
(22) Filed: **Sep. 12, 2011**
(51) **LOC (9) Cl.** 08-05
(52) **U.S. Cl.** D8/30
(58) **Field of Classification Search** D8/14,
D8/29.1-29.2, 30, 107; 219/222, 225, 227,
219/229, 238; D28/12-13, 18, 35; 392/383-385

(57) **CLAIM**

The ornamental design for a soldering iron, as shown and described.

DESCRIPTION

FIG. 1 is a perspective view of a soldering iron;
FIG. 2 is a front view thereof;
FIG. 3 is a right side view thereof; and,
FIG. 4 is a top view thereof, the opposite side being a mirror image of the side shown herein.
The portion shown by broken lines is for illustrative purposes only and forms no part of the claimed design.

1 Claim, 2 Drawing Sheets
